UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SHOCK-ABSORBING MECHANISM.

1,374,672.

Specification of Letters Patent. Patented Apr. 12, 1921.

Application filed November 6, 1919. Serial No. 336,054.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying 10 drawings, forming a part of this specification.

This invention relates to improvements in friction shock absorbing mechanism.

The object of the invention is to provide 15 a friction shock absorbing mechanism especially adapted for railway draft riggings and wherein is obtained high combined friction and spring capacity, large wearing areas, certain release, and the parts so designed that they are comparatively inexpensive to manufacture.

In the drawings forming a part of this specification, Figure 1 is a horizontal longitudinal sectional view of a railway draft rigging showing my improvements in connection therewith. Fig. 2 is a vertical transverse sectional view taken substantially on the line 2—2 of Fig. 1. Figs. 3 and 4 are views corresponding respectively with Figs. 30 1 and 2 but illustrating a somewhat different embodiment of the invention, Fig. 4 being taken on the section line 4—4 of Fig. 3. Fig. 5 is a sectional view corresponding to Fig. 3, parts being broken away, and illustrating 35 the position assumed by the friction elements at the end of the compressive stroke. Fig. 6 is a detail perspective of one of the friction shoes employed with the construction illustrated in Figs. 3, 4 and 5. Figs. 7 40 and 8 are views corresponding respectively to Figs. 1 and 2 but illustrating another embodiment of the invention, Fig. 8 being taken on the section line 8—8 of Fig. 7. And Fig. 9 is a detail perspective of one of the 45 wedges employed in the construction shown in Fig. 7.

Referring first to the construction illustrated in Fig. 1, 10—10 denote channel-shaped center or draft sills of a railway car, 50 to the inner faces of which are secured front stop lugs 11—11 and rear stop lugs 12—12. A portion of the draw bar is indicated at 13, the same being operatively connected to the shock absorbing mechanism proper by a 55 yoke 14 of well-known form. The parts are

supported in position by a detachable saddle plate 15. The shock absorbing mechanism proper, as shown, comprises, broadly, a front follower A, a combined friction shell and spring cage B, a pair of laterally movable friction shoes C—C, a central wedge D, a spring follower E, and twin arranged main springs F—F.

The combined shell and spring cage B is preferably in the form of a casting and is of 60 substantially rectangular cross section having upper and lower parallel walls 16, connecting wall 17 adapted to act as the rear follower of the draft rigging, and forward heavy side walls 18—18. The sides of the 65 casting B are open between the heavy side walls 18 and the rear walls 17 to permit lateral insertion of the twin springs F—F. Said heavy side walls 18 are provided on their outer sides with outwardly diverging 70 friction surfaces 19—19, a space being left 75 between said side walls as indicated at 20. It is evident that the spring follower E is also inserted laterally through the open 80 sides of the casting B and prior to the insertion of the springs F—F. The top and bottom walls of the casting B at the forward 85 end thereof, as indicated at 116 serve as guides for the movable friction elements C—C and D, as will be apparent from an inspection of the drawings.

The follower A is also preferably in the form of a casting and has an outer wall 21 directly engaged by the butt of the draw bar. On its inner side, the follower A is 90 provided with a pair of rearwardly diverging walls 22—22, the inner surfaces 23—23 thereof being friction surfaces in opposed 95 relation to the friction surfaces 19—19. Said follower A also has top and bottom flanges 95 or walls 24—24 in alignment with the walls 116 of the casting B and which serve as guides for the friction shoes C and wedge D. The opposed edges 25 and 26 of the follower A and casting B are normally separated a 100 distance corresponding to the permissible stroke of the draft rigging and the same will come into engagement at the end of the compressive stroke to limit further movement of the parts.

Each of the friction shoes C is provided at its outer end with a friction surface 27 inclined to the axis of the gear to correspond with the inclination of the opposed co-operating friction surfaces 23. Similarly, 110

at its rear end, each shoe C is provided with a friction surface 28 coöperable with the adjacent friction surfaces 19 of the friction shell. As is evident, upon relative approach 5 of the follower A and the friction shell, the friction shoes C will be forced or wedged laterally inwardly toward each other. On their inner sides, the shoes C are provided with friction wedge surfaces 29—29 which 10 diverge rearwardly but the included angle of which is considerably more acute than the included angle between the two friction surfaces 23 of the follower A. The friction wedge surfaces 29 of the shoes C coöperate 15 with corresponding friction surfaces 30—30 on the wedge D and it is evident that, as the shoes C—C are forced laterally inwardly toward each other they will squeeze the wedge D rearwardly or relatively toward the rear 20 wall 17 of the casting B. Said wedge D has a rearward extension 31 which bears against a plunger extension 32 on the forward side of the follower E. In order to prevent interference between the shoes C 25 and the plunger between the wedge D and follower E as the shoes C are compressed inwardly toward each other, said shoes are cut away as indicated at 33—33 to clear the plunger, as will be evident.

30 All of the parts of the shock absorbing mechanism may be held in assembled relation by means of longitudinally extending retaining bolts 34—34 which are seated at their ends in suitable pockets in the follower 35 A and casting B. In actual practice, the shoes C may be made of rolled steel plate which is suitably case hardened after the plate has been bent to proper form. In this manner I obtain rubbing friction surfaces 40 of different material between the shoes on the one hand and the follower, shell and wedge on the other hand which is desirable for the reason that it promotes longer life of the parts and produces greater friction resistance. In carrying out my invention, I 45 preferably made the friction surfaces 23—23 and 19—19 at angles of 60° to the axis of the gear and the friction surfaces 29 are made preferably at an angle of 30° to the axis 50 of the gear so that, the included angles between the friction surfaces 23—23 and 19—19 are 120° each and those between the surfaces 29—29, 60°. In this manner blunt angles between the follower A and the shoes 55 C are obtained which insures release while at the same time the actuating force is transmitted, in passing through two sets of coöperating inclined friction surfaces, at an acute angle to the wedge D, thereby obtaining highly multiplied effective spring 60 resistance. The operation is thought to be sufficiently explained in the preceding description.

Referring next to the construction illus-

trated in Figs. 3, 4, 5 and 6, the general arrangement of draft sills, stops, draw bar and yoke is the same. In the friction shock absorbing mechanism proper, I employ a follower A', a combined friction shell and spring cage B', laterally movable friction 70 shoes C'—C', central wedge D', spring follower E' and one main spring F'.

As in the construction illustrated in Figs. 1 and 2, the combined shell and spring cage B' has a friction shell proper at its forward 75 or outer end and rearwardly thereof is provided with a cylindrical spring cage designated by the reference 36, the same having a rear integral follower section 117. A single two-coil main spring F' is employed 80 instead of the twin springs F shown in the other construction.

In the construction shown in Figs. 3 to 6 inclusive, instead of forming the friction surfaces 19, 23, 27, 28, 29, and 30 flat and in 85 vertical planes as shown in Figs. 1 and 2, I form the corresponding friction surfaces in pairs which diverge in directions transversely of the shock absorbing mechanism. In other words, I form on the friction shell 90 pairs of friction surfaces 119^a and 119^b which have a very blunt included angle therebetween. Similarly on the follower A' I provide pairs of friction surfaces 123^a and 123^b which diverge from a horizontal 95 center and have a blunt included angle therebetween. The shoes C' have outer corresponding pairs of friction surfaces 127^a and 127^b, and inner pairs of friction surfaces 128^a and 128^b. On their interiors, the shoes 100 C' are formed with corresponding sets of friction surfaces 129^a and 129^b. The wedge D' has sets of friction surfaces 130^a and 130^b coöperable with the friction surfaces 129^a and 129^b respectively of the shoes C'. 105

In the construction shown in Fig. 3, the pressure-transmitting element between the wedge D' and follower E' is in the form of a plunger 37 cast integrally with the wedge D'. Only one retaining bolt 134 is used, 110 the same extending axially of the gear. In this construction, the shoes C' may be made in the form of castings.

In the construction shown in Figs. 3, 4, 5, and 6, it is evident that I obtain somewhat 115 larger areas of friction surfaces than is obtained in the construction shown in Figs. 1 and 2 but otherwise the same advantages are obtained with both constructions.

Referring next to the construction shown 120 in Figs. 7, 8 and 9, the same embodies a similar arrangement of draft sills, stops, draw bar, yoke and supporting plate as in the construction illustrated in Figs. 1 and 2. In this arrangement, I employ a combined 125 friction shell and spring cage B' corresponding to the parts B and B' of the other constructions. The member corresponding to

the followers A and A' of the two previously described constructions is indicated at A². The member A² while it performs the same functions as the members A and A', is provided with a spring cage 39 and in actual practice, the members A² and B² will be made identical to minimize the cost of manufacture. The friction shoes are indicated by the references C²—C² and instead of employing a single wedge as in the constructions previously described I employ two wedges D²—D². Two spring followers E²—E² are employed because of the double-ended arrangement and the use of the springs F²—F², one at each end of the mechanism.

The member A² is provided with friction surfaces 223 corresponding to the friction surfaces 23 of the structure shown in Fig. 1 and the member B² is provided with friction surfaces 219 corresponding to the friction surfaces 19. Similarly, each shoe C² is provided with end friction surfaces 227 and 228, corresponding respectively with the friction surfaces 27 and 28. On their interiors, the shoes C² are provided with opposed sets of friction wedge surfaces 229^a and 229^b corresponding to the friction wedge surfaces 29. Each wedge D² has friction surfaces 230—230 corresponding to the friction surfaces 30. The wedges D² are provided with pressure-transmitting plungers and in order to permit the wedges D² to slide relatively to each other, the same are centrally apertured as indicated at 40 to accommodate the plungers 231—231. The latter are equally spaced apart and those on one wedge D² slidingly passed between those of the other wedge D² as clearly indicated in Fig. 8.

In the operation of the construction shown in Figs. 7, 8 and 9, it is evident that upon relative approach of the members A² and B², the shoes C² will be forced laterally inwardly toward each other and the left-hand wedge D², as viewed in Fig. 7, will compress the right-hand spring F², whereas the right-hand wedge D² will compress the left-hand spring F². A further description of the details of the construction and operation of the arrangement shown in Figs. 7, 8 and 9 is thought unnecessary since it will be clearly understood by those skilled in the art in view of the preceding explanation of the other two forms of the invention illustrated.

I have herein shown and described the preferred manner of carrying out my invention but do not intend to be limited to the details of construction shown, except as defined by the claims.

I claim:

1. In a friction shock absorbing mechanism, the combination with a friction shell

having outwardly diverging friction surfaces, of a member opposed to said shell and movable relatively toward and from the same, said member having diverging friction surfaces extending in the opposite direction to those of the shell, a pair of friction shoes having inclined end friction surfaces coöperable with said friction surfaces of the shell and member, said shoes being forced inwardly toward each other upon the relative approach of said shell and member, said shoes having also inner wedge surfaces normally disposed outwardly beyond the shell and facing toward the latter, a wedge also normally disposed outwardly beyond the shell and interposed between and coöperating with said wedge surfaces of the shoes, a spring resistance on the opposite side of said shell to that on which said wedge is located, and means for transmitting pressure from said wedge to said spring resistance.

2. In a friction shock absorbing mechanism, the combination with two friction members normally separated and provided with opposed sets of diverging friction surfaces, said members being relatively movable longitudinally, all of said friction surfaces extending at a relatively blunt angle to the line of relative movement of the members, of a pair of friction shoes adapted for relative lateral movement and interposed between said two members, the ends of said shoes frictionally coöperating with said sets of friction surfaces, a spring resistance having one end thereof held against movement relatively to one of said members, and a wedge interposed between said shoes adapted to transmit pressure longitudinally to the opposite end of said spring resistance upon relative approach of said members, said wedge and shoes having coöperable friction surfaces extending at a relatively keen angle to the line of relative movement of said members, said wedge being normally disposed entirely outside of the member toward which it is longitudinally moved upon relative approach of said members.

3. In a friction shock absorbing mechanism, the combination with a casting having a friction shell proper and an integral transverse wall spaced longitudinally therefrom, of a spring resistance located between said shell proper and the wall and having one of its ends bearing against the wall, a member opposed to the friction shell and movable relatively longitudinally thereof, said member and shell having opposed sets of friction surfaces, friction shoes interposed between said member and shell and having the ends thereof frictionally coöperating with said sets of friction surfaces, a wedge interposed between and within said

4
shoes, the wedge and shoes having coöperating friction surfaces diverging in a direction toward said wall of the shell, said coöperating friction surfaces of the shoes and 5 wedge being disposed outwardly of said ends of the shoes which coöperate with the shell, and means, including a column, for

transmitting pressure from said wedge to the opposite end of said spring to compress the latter in a direction toward said wall. 10

In witness that I claim the foregoing I have hereunto subscribed my name this 4th day of Nov., 1919.

JOHN F. O'CONNOR.
